UNITED STATES PATENT OFFICE.

ANNA ESTELLE ENGLISH, OF PHILADELPHIA, PENNSYLVANIA.

TRAFFIC SEMAPHORE.

Application filed March 24, 1923. Serial No. 627,268.

To all whom it may concern:

Be it known that I, ANNA ESTELLE ENGLISH, a citizen of the United States, residing in the city of Philadelphia, county 5 of Philadelphia, and State of Pennsylvania, have invented an Improved Traffic Semaphore, of which the following is a specification.

My invention is a semaphore designed 10 primarily for controlling traffic at street intersections, and leading objects of the invention are to provide effective traffic control by the display of positive instructions to all persons approaching the intersection; 15 to provide display apparatus which can be readily controlled and operated either manually or electrically; and to provide apparatus which is simple in construction, durable, and readily manipulated and adjusted.

20 In its preferred form, my invention is embodied in a casing having vertical walls forming sign boards with directional indicia thereon; shutters movable relatively to the walls and having on one face thereof 25 additional directional indicia to be displayed in conjunction with the directional indicia on the sign board proper and on the other face thereof directional indicia applicable to other conditions of traffic, such latter indicia being displayed when the shutters are 30 superposed upon the indicia on the sign boards so as to conceal the latter. The vertical walls of the casing are preferably made of translucent or transparent material 35 and illuminated by a suitable lamp or lamps within the casing as well as by lamps exterior to the casing and supported by a canopy thereover so as to illuminate the directional indicia upon the walls and shutters, the latter being preferably hinged along 40 the bottom edges of the casing.

The shutters may be operated in any suitable manner, and are preferably actuated by mechanism which operates certain of the 45 shutters in one direction while moving the other shutter in the opposite direction. Such mechanism may be operated either manually or electrically.

50 The accompanying drawings illustrate a preferred embodiment of my invention. In the drawings, Fig. 1 is a side elevation of a semaphore embodying my invention, the casing and shutters being shown in transverse section; Fig. 2 is a fragmentary side 55 elevation of the upper part of the semaphore at right angles to the view shown in

Fig. 1; Fig. 3 is a transverse sectional view on the line 3—3 of Fig. 1, and Fig. 4 is a fragmentary side elevation of the casing in the position shown in Fig. 1. 60

As illustrated in the drawings, a base 1 has fixed thereto a shaft or column 2 on which is supported a casing comprising the bottom 3, frame members 4, and vertical walls 5 preferably of translucent or transparent material providing fenestrations in the casing. A canopy 6 is supported by the frame 4 above the casing and is surmounted by an illuminated globe or beacon 7. 65

Shutters 8 are hinged to the bottom 3 of 70 the casing along opposite edges thereof, and shutters 9 are hinged to the bottom of the casing along opposite edges thereof transverse to the shutters 8.

The shutters 8 have fixed thereto crank arms 8' to which are pivoted the curved ends of links 10 which are adjustably pivoted to one end of a slotted lever 11, the latter having a shaft 12 fulcrumed in the bracket 13 on the column 2. 75

The shutters 9 have fixed thereto crank arms 9' to which are pivoted the bent ends of links 14 adjustably pivoted on the lever 11 on the opposite side of its fulcrum from the connection of the links 10 therewith. 80

A link 15 has one end pivotally connected with an end of the lever 11 and its other end pivotally connected with an end of the cylindrical sleeve or collar 16 on the column 2, this collar being provided with an operating handle 17. A link 18 has an end pivotally connected with the opposite end of the lever 11 and its other end connected with a collar 19 sleeved on the collar 16 and provided with the operating handle 20. 85

A lever arm 21, fixed to the shaft 12 of the lever 11, is connected by a link 22 with an eccentric stud or pintle 23 on a revolvable disk 24 sleeved upon the shaft 25 of an electric motor 26 supported on a hanger 27 fixed to the casing bottom 3. A disk 28 is splined on the shaft 25 and has fixed thereto bars 28' terminating in a collar 28''. Governor balls 29 have arms pivoted to the shaft 25 and linked to the collar 28'' so that the rotation of the motor shaft 25 causes the balls 29 to fly outward and thereby move the collar 28'' and disk 28 longitudinally along the shaft. Friction clutch disks 30 are disposed on the shaft between the disks 28 and 24 hence the disk 24 is rotated to operate the link 22 when the motor shaft is rotated 100

with sufficient speed to cause the balls 29 to operate the clutch formed by the parts 28, 30 and 24. The rotation of the motor may be controlled by an ordinary three switch circuit, one of the switches being located on the column 2 or other convenient position for manipulation by the traffic control officer, another of the switches being positioned so as to be operated by a finger 31 on the disk 24 as the stud 23 approaches its highest position, and the third switch being positioned so as to be operated by the finger 31 as the stud 23 approaches its lowermost position.

15 Where the intersection to be controlled is formed by two streets at right angles to one another, the casing will be provided with four fenestrated walls forming a parallelogram, and when the intersection is formed 20 by streets approaching at unequal angles the casing walls will be made to conform with the angles of the intersecting streets.

When used at a right angle intersection, the translucent wall facing toward the west 25 will be marked "N—Go—S" and the shutter face which is visible from the west when the shutter is lowered will be marked "Or halt," as shown in Fig. 2. The other face of this shutter, which is visible from the west when the shutter is raised, will be marked "Go east." The translucent wall of the casing facing towards the east will be marked "S—Go—N," and the shutter face visible from the east when the shutter is lowered will be marked "Or halt." The face of the shutter visible from the east when elevated will be marked "Go west." The translucent wall visible from the south will be marked "W—Go—E" and the side 30 of the lowered shutter visible from the south will be marked "Or halt." The other side of this shutter will be marked "Go north," as illustrated in Fig. 4. The fenestrated wall and the face of the corresponding lowered 35 shutter facing the north will be marked "E—Go—W" "Or halt" and the face of the elevated shutter facing the north will be marked "Go south."

It will be understood that the traffic control officer in charge of the semaphore will 40 operate the shutters as he desires traffic to move by manipulating the handles 17 and 20, (or by throwing the switch to start the motor 26) to rock the lever 11 through the 45 respective connecting mechanisms. As the lever 11 is rocked to the position shown in Fig. 1, it acts through the links 10 and arms

8' to rotate the shutters 8 on their hinges to their lowered position and simultaneously through the links 14 pulls upon the arms 9' 60 to rotate the shutters 9 to their elevated position. When through the action of the handles 17 and 20 (or the operation of the motor 26) the lever 11 is rocked to the reverse of the position shown in Fig. 1, the 65 shutters 8 are rotated to their elevated position through the pull of the links 10 on the arms 8' and the shutters 9 are rotated to their lowered position through the thrust of the links 14 on the arms 9'. 70

The semaphore is preferably illuminated by a lamp 33 within the casing and the lamps 34 supported by the canopy 6, which may be provided with a reflecting surface to throw the illumination upon the casing walls 75 and shutters.

Having described my invention, I claim:

1. A traffic semaphore comprising a fenestrated casing, shutters hinged to said casing along transverse axes, and means for synchronously operating said shutters to cover one and uncover another of the fenestrations of said casing.

2. A traffic semaphore comprising a casing having translucent windows provided with directional indicia, shutters superposable upon windows aforesaid, and means for simultaneously operating shutters aforesaid in opposite directions.

3. A traffic semaphore comprising a casing having walls provided with directional indicia, shutters hinged relatively to said walls and superposable thereon, a fulcrumed lever, links connected with shutters aforesaid and with said lever on one side of said fulcrum, and links connected with shutters aforesaid and with said lever on the other side of said fulcrum.

4. A traffic semaphore comprising a casing, shutters hinged along the bottoms of sides of said casing, shutters hinged along the bottom of sides of said casing transversely to the shutters first named, and means for operating said shutters.

5. A traffic semaphore comprising a plurality of signs, shutters hinged relatively to said signs and superposable thereon, said shutters having directional indicia on both sides thereof, a canopy over signs, and lights carried by said canopy illuminating said signs and shutters.

In testimony whereof I have hereunto set my name this 10th day of March, 1923.

ANNA ESTELLE ENGLISH.
